(57) **CLAIM**

I claim the ornamental design for a wobbling balance board, as shown and described.

DESCRIPTION

FIG. 1 is a top, front, right isometric view of my new design for a wobbling balance board;
 FIG. 2 is a bottom, rear, left isometric view thereof;
 FIG. 3 is a front view thereof;
 FIG. 4 is a rear view thereof;
 FIG. 5 is a left view thereof;
 FIG. 6 is a right view thereof;
 FIG. 7 is a top view thereof; and,
 FIG. 8 is a bottom view thereof.

1 Claim, 4 Drawing Sheets(56)
